UNITED STATES PATENT OFFICE

JOHN CARLON, OF CRETE, NEBRASKA, ASSIGNOR OF ONE-HALF TO JOHN E. MEKOTA,
OF CRETE, NEBRASKA

GOLF BAG PROP

Application filed December 7, 1928. Serial No. 324,400.

My invention relates to golf bags and more specifically to an attachment for a golf bag for maintaining the golf bag in upright position so that it will not fall over or be blown over.

5 The primary object of my invention is the provision of an attachment having a slidably mounted pointed member which may be thrust into the turf at will for the purpose of anchoring the golf bag to the soil.

Another object is the provision of a tubular sheath in which the pointed member is adapted to slide, the sheath enclosing the body portion of the pointed member so that 15 there is little or no danger of the user pinching his fingers.

Another of my objects is the provision of a device of the character specified which is adjustable in length to fit any golf bag.

20 Another object which I have in view is the provision of a detachable device which may readily be secured to a golf bag and as readily detached therefrom.

Having in view these objects and others 25 which will be pointed out in the following description, I will now refer to the drawings, in which

Figure 1 is a view in side elevation of my device secured to a golf bag.

30 Figure 2 is a view in front elevation of the attachment on the golf bag showing both the operative and inoperative positions of the pointed member.

Figure 3 is an elevational view of the telescoping joint, a portion being broken away to 35 more clearly disclose the relationship of the parts.

Figure 4 is a plan view of the clip for latching the joint.

40 Figure 5 is a view in front elevation of the end portions of the telescoping sheath.

Figure 6 is a view in side elevation of the parts shown in Figure 5.

The support for the attachment includes 45 two tubular telescoping members 10 and 11. One of these members is larger in diameter than the other so as to snugly accommodate the other member. Either the member 10 or the member 11 may be the larger but it is 50 necessary to have a sliding relationship be-

tween the two members with one of the two snugly enclosing the other. The member 10 is provided with a hook portion 12 for engaging the top edge of the golf bag while the member 11 has a similar hook member 13 55 for engaging the lower edge of the golf bag, all as shown in Figure 1. It is readily apparent that the sheath comprising the members 10 and 11 may be extended or shortened to fit any golf bag. The joint between 60 the members 10 and 11 may be latched by means of the clip 14 having a tubular portion tightly encircling the member 10 and having also a protruding thumb piece 14a. The clip 14 fits so tightly about the member 65 10 that it compresses the member 10 about the member 11 so as to tightly latch the joint between the members 10 and 11. It should be noted that the members 10 and 11 are formed from sheet metal which is turned into cylindrical form and in which the seams are not 70 united, this making possible a compression in the member 10.

The members 10 and 11 thus form a continuous sheath extending almost the entire 75 length of the golf bag and this sheath is adapted to receive the rod 15 having a sharply pointed lower end 15a and a handle 15b at its upper extremity. The diameter of the rod 15 is slightly less than the internal 80 diameter of the tubular member 11 so that it is freely slideable therein. In the uppermost position of the rod 15 the pointed end 15a will be entirely enclosed within the tubular member 11 where it is prevented from doing 85 any damage to either the golf bag or to surrounding objects. If it is desired to compel the golf bag to maintain its upright position on the golf course it is only necessary to grasp the handle 15b, to then turn the rod 90 15 through a slight angle in order to bring the handle 15b into advantageous position and then to thrust down on the handle 15b to force the point 15a into the turf.

In the inoperative position of the rod 15 95 the handle 15b occupies the position shown in dotted lines in Figure 2, this position being at or near the upper edge of the golf bag. The lip at the upper extremity of the tubular member 10 is provided with a notch 100

for seating the handle 15b so that it will not accidentally be displaced to permit the point 15a from leaving the sheath where it might do damage. The handle 15b may also be seated to engage the upper rim of the golf bag.

The utility and advantage of my golf bag prop will be apparent to all golfers. When making a drive it is only necessary to push 10 down on the handle 15b in order to securely anchor the golf bag to the soil. After the drive has been made the golfer picks up his bag and lifts the rod 15 to its inoperative position when he is ready to move on. The 15 device is particularly useful in avoiding the loss of balls and in retrieving lost balls. When the golfer sees his ball disappear in the grass, he keeps his eyes on the spot where the ball disappeared and walks toward it. 20 The golf bag is too inconvenient to carry while searching for lost balls and if the golfer sets down the bag without taking his eyes from the position of the lost ball, the bag is liable to fall over. If he sets it down 25 carefully he loses sight of the spot where the ball disappeared. With my attachment, however, the golfer can set down the bag and anchor it to the soil without stooping over and without losing the line of vision toward 30 the lost ball.

Having thus described my invention in such full, clear, and exact terms that its construction and operation will be readily understood by others skilled in the art to which 35 it pertains, what I claim as new and desire to secure by Letters Patent of the United States is:

1. In a device of the character described, a pair of longitudinally extending guide 40 sleeves adapted to be secured in alignment on a golf bag, a rod freely slidable through said guide sleeves and adapted to be projected at its lower extremity into the ground when the bag is disposed upright upon the ground, 45 and means on the upper of said guide sleeves for securing said rod in inoperative position when the lower end thereof is withdrawn from the ground.

2. In a device of the character described, a pair of longitudinally extending guide sleeves adapted to be secured in alignment on a golf bag, a rod freely slidable through said guide sleeves and adapted to be projected at its lower extremity into the ground when the bag 55 is disposed upright upon the ground, and means on the upper of said guide sleeves for securing said rod in inoperative position when the lower end thereof is withdrawn from the ground, the lower of said guide sleeves being adapted to encase the lower extremity of said rod when said rod is secured in upwardly extended relation.

3. In a device of the character described, a pair of longitudinally extending guide sleeves each having means for attachment to

a golf bag, the inner end portions of said guide sleeves being in telescoping relation whereby said device may be adjustably secured to golf bags of different lengths, a rod freely slidable through said guide sleeves and adapted to be projected at its lower extremity into the ground when the bag is disposed upright upon the ground, and means on the upper of said guide sleeves for securing said rod in inoperative position when the lower end thereof is withdrawn from the ground, the lower of said guide sleeves being adapted to encase the lower extremity of said rod when said rod is secured in upwardly extended relation.

In testimony whereof I affix my signature.
JOHN CARLON.
